(57) **CLAIM**

The ornamental design for a remote control keypad, as shown and described.

DESCRIPTION

FIG. 1 is a front elevational view of a remote control keypad showing our new design;

FIG. 2 is a front perspective view thereof with a housing;

FIG. 3 is a top plan view thereof with a housing; and,

FIG. 4 is a side elevational view thereof with a housing.

The broken lines shown in any views showing the housing are for illustrative purposes only, and form no part of the claimed design.
